UNITED STATES PATENT OFFICE

ARTHUR G. FULLER, OF HOPEDALE, MASSACHUSETTS, ASSIGNOR, TO DRAPER CORPORATION, OF HOPEDALE, MASSACHUSETTS, A CORPORATION OF MAINE

ANTISLOUGHING DEVICE

Application filed March 12, 1931. Serial No. 521,897.

This invention relates to filling replenishing looms and is more particularly directed to means for preventing sloughing or displacement of the yarn upon filling carriers while in the hopper.

In the prior patent to John T. Kirk No. 1,595,045, dated August 3, 1926, and in the subsequent patent to Harry A. Davis, No. 1,662,000, March 6, 1928, there was shown and described an anti-sloughing device adapted to act upon the mass of filling on the carriers in the hopper and prevent endwise displacement thereof. The present invention is a further development of the anti-sloughing device with a view of providing each of the filling carriers in the hopper with an individual anti-sloughing device independent of the other filling carriers in the hopper.

Filling carriers are usually provided with filling or weft threads laid in conical layers upon the carriers and when the filling carriers are in the hopper the ends of the filling or weft threads are secured to some fixed part, so that the vibrations of the loom and the rotation of the hopper itself is liable to cause the conical end windings of filling to move longitudinally of the filling carriers and become displaced, with the result that on replenishment of filling the yarn is liable to be broken during transfer, or the filling may pass in coils over the end of the carriers during the shuttle movements.

In accordance with the present invention the hopper for the filling carriers has a series of supports or fingers preferably of resilient character to present a filling engaging portion or member in contact with the conical end windings while the filling carriers are in the hopper. In other words, each of the filling carriers is provided with an individual anti-sloughing device separate and independent from all the other anti-sloughing devices carried by the hopper.

In some cases it is desirable to provide the transerrer with a tip engaging portion in addition to the head engaging portion of the transerrer and in order that the tip engaging portion may be effectively during transfer it is preferable that it engage the end of the filling carrier or bobbin itself.

With these ends in view the anti-sloughing devices of the present invention are mounted upon the end portion of the hopper and extend therefrom adjacent the conical windings on the filling carriers at one side of the plane passing through the axis of the rotary hopper and the longitudinal axis of the filling carriers. The result of this is that the individual anti-sloughing devices will be lateral at one side of the conical end windings when a filling carrier is in transferring position, so that the transerrer may be provided with a tip engaging portion to contact with the end of the filling carrier during transfer.

The above and other features of the invention will best be made clear from the following description and accompanying drawings of one good form thereof.

In the drawings:—

Fig. 1 is a perspective view of a hopper provided with the present invention;

Fig. 2 is a perspective view of one of the supports or fingers of the anti-sloughing device detached;

Fig. 3 is a perspective view of one type of pad which may be reversibly applied to the fingers to thereby provide for wear;

Fig. 4 is an enlarged sectional elevation showing the relative position of a filling carrier and anti-sloughing device constructed in accordance with the present invention;

Fig. 5 is a plan view looking upon a filling carrier in the hopper when in transferring position; and

Fig. 6 shows a modified form of pad of yielding material.

The loom frame 1 may be of usual construction and mounted upon the loom frame is the stand of the rotary hopper comprising a foot portion 2 and an end or cover plate 3 and mounted in the cover plate is the stud or axial support 4 on which the rotary hopper is mounted for turning movement.

Extending from the hopper stand is a stud or dead shaft 5 on which is mounted the transerrer 6 which is normally under the influence of a spring 7 for maintaining the transerrer in its upper or inactive position. Extending downwardly from the hub of the

transferrer is the arm 8 to which is pivotally connected as usual the dog 9 which imparts transferring movement to the transferrer on call for replenishment of filling by engagement with the usual bunter on the lay. The parts as thus far described may all be of usual construction.

The rotary hopper in which the filling carriers 10 are mounted may likewise be of usual construction and as shown in the present instance of the invention the outer head portion 11 of the hopper is provided with tip engaging members 12 normally under the influence of springs 13 to cause the tip engaging portions to press longitudinally upon the ends of the filling carriers in the hopper.

The outer head portion 11 of the hopper is provided with a circular member 14 which forms a convenient support for the anti-sloughing devices or fingers as will presently appear.

The anti-sloughing devices or fingers 15 may be variously contrived and be supported from the hopper in a convenient manner, but as herein shown as a good practical form of the invention, each finger 15 has a spring clip portion 16 bent in contour to engage the flange or ring 14 on the hopper whereby the fingers may be individually and readily detached and applied. The spring clip 16 is conveniently formed as indicated in Fig. 2 wherein the upper portion 17 engages the top of the flange or ring 14 while the lower portion 18 passes about the lower edge of the flange or ring 14 and serves by its spring action to maintain its associated finger in operative position on the hopper.

Each finger is formed preferably as indicated in Fig. 2 wherein a resilient portion 40 extends from the spring clip at the lateral side of its associated filling carrier in the hopper. Each resilient finger is preferably, though not necessarily, provided with a pad of yielding material such for instance as that shown in Fig. 3, wherein the pad 19 is indicated as formed of a block of felt or other like suitable material provided with an opening 20 in which the resilient arm 15 may be inserted after straightening out the laterally bent portion 21 thereof and after the resilient arm 15 has been passed through the pad as described, the end portion 21 is bent laterally to maintain the pad in operative position on the finger.

55 The pad of yielding material may be variously contrived and a modification thereof is indicated in Fig. 6 wherein the pad 22 is formed of a material of suitable character, the edge portions whereof are secured together by clips 23 to thereby form an opening 24 in the pad for the reception of the resilient arm 15 of the anti-sloughing device.

As hereinbefore indicated the anti-sloughing devices extend inwardly from the outer 60 end member of the hopper at the lateral side

portion of the associated filling carrier, such that when a filling carrier has reached transfer position in the hopper the anti-sloughing device will present no obstruction to the downward movement of a tip engaging portion mounted on the transferrer, so that said tip engaging portion as indicated in Fig. 1 at 25 may during this downward movement engage the exposed end portion 26 of the filling carrier or bobbin and in conjunction with the usual head portion of the transferrer effect a proper transfer of the filling carrier to the shuttle.

The above described condition is illustrated in Fig. 5 wherein the line *a*—*b* represents a plane passing through the axis of the hopper and the longitudinal axis of the filling carrier, and it will be noted from Fig. 5 that when the filling carrier is in transferring position the anti-sloughing device bears upon the conical end windings at one side of such plane so that it presents no obstruction to the transfer of the filling carrier from the hopper to the shuttle by the engagement of the head and tip engaging portions of the transferrer.

From the construction described it will be apparent that the present invention provides an individual anti-sloughing device for each of the filling carriers in the hopper and that such anti-sloughing devices are individually or self-contained irrespective of the other anti-sloughing devices on the hopper.

It will be apparent from the disclosures herein that the individual and separate anti-sloughing devices afford simple and effective means for preventing sloughing or displacement of the yarn or filling on the filling carriers while in the hopper.

Should the anti-sloughing devices comprise not only the resilient fingers 15 but a reversible pad as well, it is obvious that upon undue wearing of one portion of the pad as herein described the pad itself may be reversed in position on the resilient finger to thereby present a new and fresh anti-sloughing surface to bear against the conical end windings at one side of the plane passing through the axis of the hopper and the longitudinal axis of the filling carrier.

Claims:

1. In a filling replenishing loom, the combination of a hopper for filling carriers having filling wound thereon, supports on the hopper each having a separate filling engaging member independent of other supports to individually bear upon the conical end windings of its associated filling carrier to prevent sloughing or displacement of the yarn on the filling carrier while supported in the hopper and to permit the unobstructed movement of a bobbin tip engaging member between the filling engaging members during transfer.
2. In a filling replenishing loom, the com- 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

bination of a hopper for filling carriers having filling wound thereon, resilient fingers extending from the end of the hopper, each provided with a separate pad of cushion material to bear upon the conical end windings of the filling on the associated filling carrier while in the hopper to prevent sloughing or displacement of the yarn and to provide a passage for a bobbin tip engaging member during transfer.

3. In a filling replenishing loom, the combination of a hopper for filling carriers having filling wound thereon, resilient fingers extending from the end of the hopper along the lateral side of the filling carriers to bear upon the conical end windings, such that when a filling carrier is in transferring position the associated resilient finger will not obstruct the movement of a tip engaging member on the transferrer.

4. In a filling replenishing loom, the combination of a hopper for filling carriers having filling wound thereon, a series of resilient fingers extending from the end of the hopper along the lateral side of the wound filling carriers, a separate pad of yielding material secured to each resilient finger to bear upon the lateral side of the conical end windings to prevent sloughing or displacement of the yarn so that when a filling carrier is in transferring position the associated pad will bear upon the side of the conical end winding in a substantially vertical plane.

5. In a filling replenishing loom, the combination of a rotary hopper for filling carriers having filling wound thereon, fingers mounted on the hopper and having a filling engaging member the bearing face of which is at one side of a plane passed through the axis of the hopper and the longitudinal axis of the filling carrier in the hopper to bear upon the lateral side portion of the conical end windings and prevent sloughing or displacement of the yarn on the filling carriers while in the hopper.

6. In a filling replenishing loom, the combination of a rotary hopper for filling carriers having filling wound thereon, fingers extending from the outer end portion of the hopper at one side of a plane passed through the axis of the hopper and the longitudinal axis of a filling carrier to prevent sloughing or displacement of the conical end winding on a carrier in the hopper.

7. In a filling replenishing loom, the combination of a rotary hopper for filling carriers having filling wound thereon, fingers extending from the outer end portion of the hopper at one side of a plane passed through the axis of the hopper and the longitudinal axis of a filling carrier to prevent sloughing or displacement of the conical end winding on a carrier in the hopper, said fingers being provided with spring clips for detachably

holding the fingers connected to the end portion of the hopper.

8. In a filling replenishing loom, the combination of a rotary hopper for filling carriers having filling wound thereon, resilient fingers extending from the end of the hopper, a separate reversible pad of yielding material carried by each finger to bear laterally upon the conical end windings of the associated filling carrier when in transferring position that the yielding materials will not obstruct the movement of a tip engaging member between them during transfer.

9. In a filling replenishing loom, the combination of a hopper for filling carriers having filling wound thereon, a transferrer having a bobbin tip engaging member, separate fingers extending from the end of the hopper to individually bear upon the conical end windings of the filling carriers and provide a passage way between them for the bobbin tip engaging member during transfer of a filling carrier from the hopper.

In testimony whereof, I have signed my name to this specification.

ARTHUR G. FULLER.
